UNITED STATES PATENT OFFICE.

JOHN ALBERT BURR, OF AGAWAM, MASSACHUSETTS, ASSIGNOR OF THREE-FOURTHS TO OSCAR L. KING, OF SAME PLACE.

LAWN-MOWER.

SPECIFICATION forming part of Letters Patent No. 624,749, dated May 9, 1899.

Application filed September 8, 1898. Serial No. 690,464. (No model.)

To all whom it may concern:

Be it known that I, JOHN ALBERT BURR, a citizen of the United States of America, and a resident of Agawam, in the county of Hampden and State of Massachusetts, have invented 5 certain new and useful Improvements in Lawn-Mowers, of which the following is a full, clear, and exact description.

This invention relates to improvements in 10 lawn-mowers of the most common type, comprising traction-wheels and a rotary cutter or shear operating in conjunction with a fixed bar relative to which the curved knife of the rotary cutter has shearing actions.

15 The object of my invention is to provide a casing which wholly incloses the operating-gearing so as to prevent it from becoming choked by the grass or clogged by obstructions of any kind.

20 The improved lawn-mower is illustrated in the accompanying drawings, in which—

Figure 1 is a plan and partial horizontal section of the machine, Fig. 2 being a side elevation with a portion of one of the side cheek 25 members broken away for clearer illustration.

Similar characters of reference indicate corresponding parts in both views.

20 A represent the traction-wheels, fixed on the end portion of the shaft B, outside of which 30 are the cheek-plates or castings C C, the yoke and handle D being provided in the usual manner for pushing or drawing the lawn-mower.

The traction-wheels are constructed with 35 comparatively wide rims and with a web or spokes a uniting the hub portion thereof with the rim, the hub portion a² being comparatively narrow, so that the circular portion b of each cheek-plate may be well disposed with- 40 in the cup-like traction-wheels.

Each cheek-plate C has the forward portions d d thereof outwardly offset, as more 45 plainly seen in Fig. 1, these standing considerably outwardly beyond the outer faces of the traction-wheels and support between them the central shaft of the rotary cutter G, which

40 comprises the shearing knives or blades h, constructed as usual, with the exception that they are unusually long, being longer than the 50 distance between the outer faces of the wheels A A. These cheek-plate extensions d d also

support between them the counter-shaft i and the fixed bar j of the cutter, and the ground-roller k is hung in the adjusting-arms m m.

Loosely mounted on the shaft B is the gear-wheel o, having as a part thereof the ratchet-wheel o², a spring-pawl o³, provided on the inner face of one of the traction-wheels, engaging in the teeth of said ratchet-wheel o² for causing the rotation of the said gear-wheel o in unison with the turning of the traction-wheels when the latter roll forwardly as the machine is pushed in its work.

The gear-wheel p on the counter-shaft i is in mesh with the gear-wheel o, wheel p being 65 of less diameter than the one o, whereby the forward rotations of the latter will cause faster rotation of the wheel p and the counter-shaft, which has also thereon, near its outer end, the gear-wheel q, which is in mesh with the gear-wheel t, affixed to the arbor or shaft f of the 70 rotary cutter.

The cheek-plate extension d at one side of the machine is formed chambered, as seen at d², the same comprising the inner wall or face 75 10 and the marginal rib 12, against which latter the cap-plate 13 is screwed or otherwise secured, and a casing in the form of a chambered shell or casting (indicated at u) is provided to inclose the gearing at p o o², &c., the 80 same being supported upon the shafts B i, as seen in Fig. 1.

By making the side cheek-plates with the forward extension members d d decidedly outwardly offset beyond the outer faces of the 85 traction-wheels provides for the mounting between the forward ends of the cheeks of a rotary cutter having a length quite a little exceeding the distance between the outer faces of the traction-wheels, and hence it becomes possible to cut the grass more closely 90 to a building or other object than would be possible were the ends of the rotary cutter disposed within the planes coincident with the outer faces of the said wheels, and it will be 95 seen that in the use of the machine its every pass will cut the grass in a path wider than that comprised between the traction-wheels, so that the disadvantage of having one of the wheels bed down the grass just outside of the 100 cut path or swath at every pass is overcome.

Having thus described my invention, what

I claim, and desire to secure by Letters Patent, is—

5 In a lawn-mower, the shaft B, the driving-wheels secured thereto and having recesses formed in their sides, the shafts i, f, extending parallel with the shaft B, the gears o, p, secured to the shafts B, i, the pawl and ratchet, and the casing u which incloses the gears, and has the circular flange upon its inner side ex-
10 tending into the recess of the wheel A, combined with the cheek-plates which form bearings for the shafts B, i, and which are made

to extend into the recesses on the outer sides of the wheels, and which cheek-plates are provided with the outward extensions, the gears 15 q, t, secured to the ends of the shafts i, f, and the cap-plate 13, which closes over the gears, substantially as specified.

Signed by me, at Springfield, Massachusetts, this 31st day of August, 1898.

JOHN ALBERT BURR.
